UNITED STATES PATENT OFFICE.

FRANK KLICPERA, OF RACINE, WISCONSIN.

DESIGN FOR A SASH-FASTENER.

57,135.

Specification for Design.

Patented Feb. 22, 1921.

Application filed May 25, 1920. Serial No. 384,162. Term of patent 14 years.

To all whom it may concern:

Be it known that I, FRANK KLICPERA, a citizen of the United States, residing at Racine, in the county of Racine and State of Wisconsin, have invented a new, original, and ornamental Design for Sash-Fasteners, of which the following is a specification, reference being had to the accompanying drawing, forming part thereof.

Figure 1 is a side elevational view, and Fig. 2 is a top plan view.

I claim:

The ornamental design for a sash fastener, as shown.

In testimony that I claim the foregoing I have hereunto set my hand at Racine, in the county of Racine and State of Wisconsin.

FRANK KLICPERA.
